UNITED STATES PATENT OFFICE.

FAY HUNT, OF NEW YORK, N. Y.

DERRICK.

Application filed July 15, 1926. Serial No. 122,664.

My invention relates to derricks and has particular usefulness as embodied in an improvement on the derrick forming the subject-matter of United States Letters Patent, 5 Number 926,191, granted to me June 29, 1909.

The general object of my invention is to provide a novel form of gudgeon for the lower end of the mast and of a character to 10 be employed for running therethrough a hoist cable, the invention including also co-ordinated means to guide the hoist cable at the top of the mast.

The nature of my invention and its distinguishing features and advantages will 15 clearly appear as the description proceeds.

Reference is to be had to the accompanying drawings forming a part of this specification, it being understood that the drawings 20 are merely illustrative of one example of the invention.

Figure 1 is a side elevation of my improved derrick embodying my present invention showing the auxiliary frame in its 25 inoperative position within the plane of the main frame;

Figure 2 is a horizontal section on the line 2—2 of Figure 1, the auxiliary frame being 30 swung around to a position substantially at right angles to the position shown in Figure 1;

Figure 3 is a view at the mast, said view being partly in side elevation and partly in 35 vertical section;

Figure 4 is a horizontal section on the line 4—4, Figure 6;

Figure 5 is a horizontal section on the line 5—5, Figure 3;

Figure 6 is a vertical sectional view at the 40 base of the mast;

Figure 7 is a horizontal section on the line 7—7 of Figure 3.

In my patented derrick, referred to, there 45 is a main frame and an auxiliary frame each including sills and stiff legs. In the present example of my invention, the numeral 10 represents the plates secured to the main sill, 11, and 12 upper and lower straps secured to the auxiliary sill 13. The numeral

50 14 indicates the mast having integral side plates 15 forming the upper terminal having secured thereto in any suitable manner the upper gudgeon pin 16 over which is disposed an inverted U-shaped fitting 115 to 55 which the main stiff leg 17 and the auxiliary stiff leg 18 are secured by goosenecks 19, 20.

The numeral 21 indicates the adjusting chain connection for the head of the boom 22 and 60 23 indicates a hoist cable running at the top over a sheave 24 carried by one of the side plates 15.

The numeral 25 indicates my improved gudgeon pin provided in accordance with the present invention at the base of the mast. Said gudgeon pin 25 is secured to 65 the mast through the medium of the threaded upper end 26 of said gudgeon pin, which receives a nut 27 and angle washer 28, disposed within the mast 14. The mast 14 is provided with angle side plates 30 to which 70 the boom 22 is pivoted at its lower end as at 32.

The gudgeon pin 25 passes through the straps 12 so as to turn therein, there being washers 33 on said gudgeon pin above and 75 below straps 12. An inverted U-shaped yoke 34 is secured to the plates 10 of the main sill 11 and a collar 35 is provided on the mast at the lower end and secured by keys or pins 36. The described assemblage 80 at the lower end of the mast permits the sills to be swung laterally through the desired arc, thereby disposing the sills in any particular direction in setting up the derrick as a right or left-hand derrick.

It is to be observed that the lower gudgeon pin 25 is tubular and forms a through-passage for the hoist cable 23 which may be run from the lower end of the gudgeon pin and main sill 11 to any point desired. The 90 construction described simplifies the provision for leading the hoist cable upwardly through the mast and sill fittings by reason of the gudgeon pin 25 having the through-bore for said cable.

I would state furthermore that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I 95 claim:

1. In a derrick, a mast, means supporting the lower end of the mast, a sill, a tubular gudgeon pin connected with the mast at the lower end, and means for swiveling the lower end of said tubular gudgeon to the 100 said sill so that the sill can swing laterally on said tubular gudgeon.

2. In a derrick, a mast, means supporting the lower end of the mast, a sill, a tubular gudgeon pin connected with the mast at the lower end, and means for swiveling the lower end of said tubular gudgeon to the said sill so that the sill can swing laterally on said tubular gudgeon, the said tubular gudgeon affording a passageway there-

through to the mast for the running of a hoist cable so that the hoist cable may move 10 longitudinally in the direction of the derrick while said cable may be without interference therewith by the sill when moved laterally.

FAY HUNT.
